UNITED STATES PATENT OFFICE

GEORGE C. CLEAVES, OF WOLLASTON, MASSACHUSETTS, ASSIGNOR TO INDUSTRIAL BRUSH COMPANY, OF QUINCY, MASSACHUSETTS, A CORPORATION OF MASSACHUSETTS

BRUSH

Application filed February 4, 1930. Serial No. 425,786.

This invention relates to a brush and to a method of making the same.

One object of the invention is to provide a novel and superior brush which may be economically manufactured and in which the brush material is secured upon a supporting member in a novel and efficient manner whereby a durable, efficient and superior brush is produced.

10 A further and more specific object of the invention is to provide a novel rotary brush which possesses characteristics which are adapted particularly for certain industrial purposes and which may be made at minimum expense.

15 A still further object of the invention is to provide a novel method of making the improved brushes.

With these objects in view and such others as may hereinafter appear, the invention consists in the brushes and method hereinafter described and particularly defined in the claims at the end of this specification.

20 In the drawings illustrating the preferred embodiment of the invention, Fig. 1 is a longitudinal sectional view illustrating the construction of the present brush; Fig. 2 is an enlarged detail in longitudinal section; Fig. 3 is a perspective view illustrating the preferred manner in which the individual brush material is formed into a strip to be used in the construction of the present brush; Fig. 4 is a modified form of strip which may be used for such purpose; and Fig. 5 is a 25 cross-section taken on the line 5—5 of Fig. 1.

30 In general the present invention contemplates a brush in which brush material in helical form is interposed between the convolutions of a helical retaining member to be held in brush forming position, and in the preferred form of the invention the retaining member may comprise a relatively stiff helical spring, and the brush material may 35 preferably be preformed into the form of a strip, as for example into the form of the woven web or strip illustrated in my Patent No. 1,663,584, in which successive bundles are woven by means of binding strands into strip form. The present construction of brush is particularly adapted for the manu-

facture of elongated cylindrical brushes, and in such an embodiment of the invention it is preferred to construct the brush upon a rigid metal tubular support with a helical spring wound thereon and with the strips of brush material helically wound around the support so that the individual brush material stands out at right angles to the support and with the butt ends of the strips interposed between and clamped by the convolutions of the helical spring. The strips of the brush material may be also cemented between the convolutions of the spring. Provision is made for enabling the tubular supporting member to be mounted upon a shaft in order to enable the brush to be rotated.

35 Referring now to the drawings, the different features of the invention are illustrated as embodied in an elongated rotary brush adapted for use in the tanning, printing and allied industries for the distribution of color or other material upon the leather, cloth, or other material, and wherein 10 represents the supporting member comprising preferably an elongated steel tube into the 40 ends of which may be driven plugs 12 secured in fixed relation to the tube by pins 13, or in any other convenient manner. The plugs 12 are each provided with a central opening 14 for the reception of the shaft 45 upon which the brush is to be mounted in the machine in which it is to be used. The tubular supporting member 10 is provided with a helical brush retaining member comprising preferably a tempered, relatively stiff 50 spring 16, the sides 17 of each convolution of which are preferably flattened to afford a substantial bearing to retain brush material 55 interposed between the adjacent convolutions of the spring 16.

60 The brush material 20 may and preferably will be formed into strip form, and the strip may be wound around the supporting tube 10 with the butt ends of the brush material interposed between the adjacent convolutions of the spring. In making the illustrated cylindrical brush, I prefer to first assemble the spring 16 upon the tube 10, with the size of the spring such that it will more or less snugly engage the tube prior to the intro- 65

duction of the brush material in between the convolutions of the spring. One end of the spring 16 is then held in fixed relation to the tube, either by a pin 22 or by other suitable 5 clamping means, and then succeeding convolutions of the spring are spread apart by means of a suitable tool such as a wedge, and the brush material, preferably as a preformed strip and preferably having the butt ends 10 dipped in a cementitious material such as rubber latex, is then wound around the support with the butt end of the brush material interposed between the convolutions of the spring which have been spread apart. The 15 wedging operation and the introduction of the brush material is continued until the brush material has been interposed between all of the convolutions of the spring, whereupon the second end 24 of the spring is then 20 secured in fixed relation to the tubular supporting member 10 as by a second pin 26 or otherwise.

In producing the illustrated cylindrical brush, the brush material may and preferably 25 will be first woven into strip form in accordance with my Patent No. 1,663,584, above referred to, such a strip being illustrated in Fig. 3. In producing the brush it is preferred to utilize a single continuous strip of 30 the brush material helically wound around the supporting tube 10 between the convolutions of the spring so that in the completed brush the brush material is all in the form of a single strip, thus contributing to the durability 35 of the brush as well as the economy of manufacturing the same. The coil spring is, as above stated, preferably provided with flattened sides as illustrated at 30 to afford a substantial bearing area for the spring in engaging and clamping the brush material.

Instead of forming the brush material into strip form in accordance with my patent above referred to in which the tufts of the brush material are connected by binding 45 strands woven in and out around the bundles, I may also form the brush material into strip form in other known ways, such for example as that illustrated in Fig. 4, in which the individual bristles are connected into strip form 50 by binding tapes 40, 42 laid upon the opposite sides of the mass of bristles forming the strip and stitched by a plurality of rows of stitching to each other and through the interposed mass of bristles.

From the description thus far it will be observed that the present brush possesses certain features of advantage which contribute to the economy of its manufacture and the efficiency of its operation. The brush material 60 being preferably in the form of a pre-formed strip may be economically assembled with relation to the supporting member, and when assembled is retained by the cooperation of the spring therewith and also by the 65 continuity of the strip itself. The present

construction of brush lends itself to the use of a steel or other metal tube which may be imperforate and possess considerably greater strength and durability than the perforate wooden hubs heretofore used. Experience 70 has shown that such perforate hubs gradually sag, particularly with elongated brushes such as are used in the tanning industry thus shortening the life of the brush considerably and preventing its most efficient operation. The 75 helical form in which the brush material is wound around the tubular supporting member enables the brush as it is rotated to present a continuous surface of the brush material to the work, avoiding the formation of streaks 80 and other irregularities therein.

Another important advantageous feature of the present brush resides in the ease with which it may be refilled after it has become worn in use. The strip of old brush material may be removed by softening the latex or other cement with solvent, spreading the convolutions of the spring and then removing the worn brush strip. In this manner a new brush may be produced using the old 90 tubular support and the spring, contributing to the economy of manufacture.

While the preferred embodiment of the invention has been illustrated and described, it will be understood that the invention may be 95 embodied in other forms within the scope of the following claims.

Having thus described the invention what is claimed is:—

1. A rotary brush comprising a metal supporting tube, a coiled spring wound thereon, and brush material interposed between coils of the spring and secured in operative position upon the supporting tube with the butt ends of the brush material resting against the 100 surface of the tube, said coiled spring being formed of material having only sufficient flexibility to permit it to be shaped into helical form and with the convolutions of the spring spread apart by the interposed brush material whereby the tendency of the convolutions of the spring to return to their normal 105 position exerts a clamping action on the brush material.

2. A rotary brush comprising an elongated supporting member, a coiled spring wound thereon, and brush material secured in operative position upon the supporting member by the coils of the spring, said spring being relatively non-flexible but capable of 110 being spread longitudinally by the brush material interposed between the convolutions of the spring to be clamped by the spring action thereof.

3. A rotary brush comprising a coiled spring, brush material interposed between the coils of the spring to be secured in fixed relation thereto and to spread the coils of the spring so that the spring exerts a clamping 115 action upon the brush material.

4. A brush comprising a supporting member, a coiled spring operatively positioned thereon, and brush material interposed between the coils of the spring to be secured in operative position upon the supporting member and to spread the coils of the spring so that the spring exerts a clamping action thereon.

5. A rotary brush comprising an elongated metal supporting tube, a helically wound coiled spring upon the tube, and a helically wound strip of brush material interposed between adjacent coils of the spring to be secured upon said supporting member and to spread apart the coils of the spring so that the spring exerts a clamping action thereon.

6. A rotary brush comprising an elongated metal supporting tube, a coiled spring wound thereon, and a woven strip of brush material wound upon the support with portions of the strip clamped between the adjacent coils of the spring by the tendency of the coils of the spring to resume their normal position.

7. A brush comprising a supporting member provided with a helical retaining member, and brush material in strip form interposed between and secured by the adjacent individual sections of the retaining member, said helical retaining member being formed of a relatively stiff non-flexible material whereby it retains its helical formation both when positioned on and removed from the supporting member.

8. A brush comprising a metal tube, a preformed metal coiled spring mounted thereon, capable of resuming its normal position when distorted, a preformed strip of brush material wound helically around the supporting tube and with the butt ends of the strip of brush material resting against the surface of the tube and positioned between adjacent convolutions of the spring to spread the same apart and thereby cause the brush material to be clamped by the convolutions of the spring.

9. A brush comprising a supporting member, a preformed strip of brush material arranged in helical form on the supporting member and extending substantially perpendicularly to the surface thereof, and a helical metal retaining member for securing the brush material upon the supporting member, said helical metal retaining member being capable of retaining helical formation both when positioned upon and removed from the supporting member.

In testimony whereof I have signed my name to this specification.

GEORGE C. CLEAVES.
